UNITED STATES PATENT OFFICE.

SAM H. KANMACHER, OF SCHENECTADY, NEW YORK, ASSIGNOR TO GENERAL ELECTRIC COMPANY, A CORPORATION OF NEW YORK.

CONTROLLER FOR ELECTRIC CIRCUITS.

No. 820,877.

Specification of Letters Patent.

Patented May 15, 1906.

Application filed June 22, 1904. Serial No. 213,589.

To all whom it may concern:

Be it known that I, SAM H. KANMACHER, a citizen of the United States, residing at Schenectady, county of Schenectady, State of New York, have invented certain new and useful Improvements in Controllers for Electric Circuits, of which the following is a specification.

My invention relates to controllers for electric circuits, and is particularly applicable to systems employing local and distant control.

In an application for United States Letters Patent, Serial No. 208,892, filed by Arthur A. Buck May 20, 1904, and assigned to the General Electric Company, is described a system of control for motor-operated bulkhead-doors and similar devices. In this system a controlling-switch for the motor is placed at each door which is arranged to connect the motor for raising and lowering the door. A solenoid is provided for moving each switch to the proper position to connect the motor for lowering the door. By means of these solenoids a number of doors may be closed from a distant point. The switch is furthermore arranged so that it may be moved manually to either position for raising or lowering the door without disturbing the circuit of the solenoid. In this way a man at the door can take control away from the distant station temporarily, so as to raise the door, but when he releases the switch it will return to the position for lowering the door, provided the circuit of the solenoid has been closed at the distant point.

In an application, Serial No. 213,254, filed by J. W. Kellogg June 20, 1904, and assigned to the General Electric Company, is disclosed a modified arrangement of a switch and its operative connections for such a system. In the arrangement of this latter application both operative positions are placed on the same side of the off position, the lowering position being between the off and the raising position. With this arrangement it is not necessary to move the switch through the off position when shifting it from lowering to raising, and since this movement is against the tension of the spring this reduction of the necessary length of movement is an advantage. The operative connections of the switch are modified so as to permit a control similar to that in the first-mentioned application. In the arrangements described in both of the above applications two springs are

employed. One spring, which serves normally to hold the switch in off position, is connected to the distant-control device. By straining this spring the distant-control device is enabled to shift the switch to an operative position. The second spring connects the switch to the distant-control device. By straining this latter spring manually the switch may be moved to its other operative position without disturbing the distant-control device.

My invention consists in an improvement in the switch described in the latter of the above-mentioned applications, in which both operative positions are on the same side of the off position. I take advantage of this arrangement of the switch-contacts to dispense with one of the springs. I employ a single spring connected directly to the switch to hold it normally in off position, and I employ simply a lost-motion connection between the switch and the distant-control device to permit the desired movement of the switch without disturbing said device. By "lost motion" I mean a loose yet positive direct mechanical engagement between the two parts.

My invention will best be understood by reference to the accompanying drawings, in which—

Figure 1 shows a front elevation of a controlling-switch and its operating mechanism arranged in accordance with my invention, the front part of the casing being removed. Fig. 2 shows a side elevation of the same, the casing being shown in cross-section; and Fig. 3 is a diagram showing the electrical connections of the several parts of the switch as employed in a system for the local and distant control of one or more motors.

Referring first to Figs. 1 and 2, K represents a water-tight casing, in which is journaled the shaft *a*, which is rotatable by means of the hand-wheels *a'*, one or both of which may carry an index *a''*. Mounted on the shaft *a* is the movable switch member *A*, which carries the movable contacts *c'* to *c''*, three of these contacts being shown in Fig. 1. Supported from the casing are stationary contacts *f'* to *f''*, which are arranged in two groups of four each, as shown. These contacts are so positioned that when the switch member *A* is moved to bring contact *c''* into engagement with contact *f'*, as shown in Fig.

1, contact c^6 will be brought into engagement with contact f^8 , and when the motion of movable member A is continued to bring contact c^6 into engagement with finger f^4 contact c^9 will be brought into engagement with finger f^8 . Movable member A is normally held in the off position, as shown by a tension-spring F, one end of which is connected to a pin j on the casing and the other end to a pin g on the 5 cam-plate G, carried by shaft a. The tension of the spring F presses cam-plate G against the stop g' , mounted on the casing. Since both operative positions are on the same side of the off position, a single spring 10 suffices for holding the switch normally at off position.

H is a pivoted member carrying the roller h and pressed against the surface of cam-plate G by the tension-spring I. The cam-plate is shaped so that roller h is brought into engagement with the shoulder g^3 when the shaft a is moved to bring contact c^3 into engagement with finger f^1 . Member H thus forms a yielding stop which enables the shaft 15 to be moved quickly and positively to its first position.

The distant control is accomplished by means of the solenoid B, which is provided with a movable core b. Core b engages the 20 lever D, pivoted at d, which carries at its forward end the link E. Link E is provided with a pin which engages a slot e in the movable switch member A. The solenoid B is provided with a stop b', which limits the 25 upward movement of core b when solenoid B is energized. This stop is so positioned that when solenoid B is energized member A is rotated a sufficient amount to bring contacts c^3 and c^6 into engagement with fingers f^4 and f^8 , respectively. This position of the contacts connects the motor for lowering the 30 door, as will be hereinafter described.

If a man at the door desires to raise the door while the solenoid is energized and the 35 switch is in the position for lowering, he can rotate the shaft a manually to bring contacts c^6 and c^9 into engagement with fingers f^4 and f^8 , respectively, which is the position for raising the door, as will be hereinafter described. 40 This movement from lowering to raising position is freely permitted by the lost-motion connection between the core b and switch member A, formed by the pin and slot. The slot e is made of sufficient length to permit 45 the necessary movement of member A in passing from lowering to raising position. When solenoid B is not energized, shaft a may obviously be freely moved to either lowering or raising position. In passing from 50 the off position, as shown in Fig. 1, to lowering position, link E will not be moved, since the slot e is of sufficient length to enable the member A to be moved from off to lowering position. If it is desired to pass through the 55 lowering position to the raising position, the

lower end of slot e will engage the pin carried by link E and the core b will be raised, or if slot e is made long enough core b will not be moved. In either case the construction of the switch permits of free manual control, 70 while, on the other hand, since the solenoid-circuit is not disturbed by the manual control, the switch will return to the off or lowering position when released by hand, according as the solenoid-circuit is opened or closed. 75

In Fig. 3 is shown a diagram of the circuit connections of the switch as employed in a system of local and remote control having a plurality of motors. Two motors M and M' are indicated with two controlling-switches C 80 and C'. L represents a source of current connected to the line-wires l l'. B and B' represent the windings of the solenoids, by means of which the switches are moved to lowering position from a distance, as has been heretofore 85 described. These solenoids have their circuits completed through the switches S and S', which are at the distant-control station. R and R' represent two resistances which are connected always in circuit with the motors, 90 so that in case the motor-circuit is not broken when the door has reached the extremity of its travel and the motor has stopped, the current through the motors will be kept at a value too low to injure the motors. The resistances r and r' are connected in shunt to the motor-armatures when the motors are connected for lowering the door. The purpose of these resistances is to produce a strong field, thereby preventing the motor from racing and giving it a high torque for closing the 95 door.

The circuit connections are as follows: When the switch C is moved into its first or lowering position, either manually or by 100 means of the solenoid B, a circuit is closed as follows: from line-wire l to finger f^2 , to contact c^4 . Here the current divides, part passing through finger f^2 and motor-armature M and part passing to contact c^4 , finger f^5 , and resistance r. Resistance r is thus placed in shunt with motor-armature M. The current then passes through resistance R, finger f^7 , contact c^2 , contact c^3 , finger f^3 , motor-field m, finger f^4 , contact c^6 , contact c^9 , finger f^8 , and line-wire l'. When the controller C' is moved to its second or raising position, the resistance r is open-circuited and the motor-field is reversed by means of the following connections: from line-wire l, finger f^2 , contact c^4 , finger f^5 , motor-armature M, resistance R, finger f^7 , contact c^8 , contact c^6 , finger f^4 , motor-field m, finger f^3 , contact c^5 , contact c^9 , finger f^8 , line l'. The controller C' differs only from controller C in the electrical connections of its stationary fingers. The circuit connections produced are the same with both controllers. The difference in the connections is merely a matter of convenience, according as to which side of the door the controller has to be placed 115 120 125 130

It will be noted that one finger is left blank in both controllers, the blank finger being different in the two.

Other arrangements and connections of the controller-contact may of course be employed without departing from the spirit of my invention. Furthermore, changes may be made in the construction and arrangement of the several parts of the control-switch. Accordingly, I aim to cover all such modifications which are within the spirit and scope of my invention.

What I claim as new, and desire to secure by Letters Patent of the United States, is—

1. In combination, a switch having a plurality of operative positions on one side of its off position, means controllable from a distance for moving said switch to an operative position, a stop for said moving means to arrest said switch at said position, a lost-motion connection between said moving means and said switch whereby the movement of the switch may be continued manually to another operative position, and means connected directly to said switch for holding the switch normally in off position.

2. In combination, a switch having a plurality of operative positions on one side of its off position, an electroresponsive device adapted and arranged to move said switch to an operative position, a lost-motion connection between said device and said switch whereby the movement of said switch may be continued manually to another operative position without moving said device, and means connected directly to said switch for holding the switch normally in off position.

3. In combination, a switch having a plurality of operative positions on one side of its off position, an electromagnet adapted and arranged to move said switch to an operative position, a stop for arresting the movement of said electromagnet when said switch reaches said operative position, a lost-motion connection between said switch and said electromagnet whereby the movement of said switch may be continued manually to another operative position, and means connected directly to said switch for holding the switch normally in off position.

4. In combination, a switch having a plurality of operative positions on one side of its

off position, means controllable from a distance for moving said switch to an operative position, a lost-motion connection between said switch and said moving means whereby the movement of said switch may be continued manually to another operative position without moving said moving means, and means connected directly to said switch for holding the switch normally in off position.

5. In combination, a switch, a stop engaging said switch when in off position, an electroresponsive device adapted and arranged to move said switch away from said stop to an operative position, a lost-motion connection between said device and said switch whereby the movement of said switch may be continued manually to another operative position without moving said device, and a spring connected directly to said switch and normally pressing the switch against said stop.

6. In combination, a switch, a stop engaging said switch when in off position, an electroresponsive device adapted and arranged to move said switch away from said stop to an operative position, means for arresting said device when the switch reaches said operative position, a lost-motion connection between said switch and said device whereby the movement of said switch may be continued manually to another operative position, and a spring connected directly to said switch and normally pressing the switch against said stop.

7. In combination with an electric motor, a reversing-switch for said motor having both operative positions on one side of its off position, means controllable from a distance for moving said switch to one of its operative positions, a lost-motion connection between said switch and said moving means whereby the movement of said switch may be continued manually to the other operative position, and means connected directly to said switch for holding the switch normally in off position.

In witness whereof I have hereunto set my hand this 20th day of June, 1904.

SAM H. KANMACHER.
